UNITED STATES PATENT OFFICE.

DANIEL RAMSAY, OF PHILADELPHIA, PENNSYLVANIA.

AUTOMATIC DRILLING-MACHINE.

SPECIFICATION forming part of Letters Patent No. 694,784, dated March 4, 1902.

Application filed July 12, 1901. Serial No. 68,090. (No model.)

To all whom it may concern:

Be it known that I, DANIEL RAMSAY, a citizen of the United States, residing in Philadelphia, Pennsylvania, have invented certain 5 Improvements in Automatic Drilling - Machines, of which the following is a specification.

The object of my invention is to simplify the construction of an automatic drilling or 10 boring machine, to provide for ready adjustment of the parts, and generally to improve the efficiency of the machine and adapt it to the various classes of work for which it is intended.

15 In the accompanying drawings, Figure 1 is a front view of an automatic multiple boring or drilling machine constructed in accordance with my invention. Fig. 2 is an end view of the machine looking in the direction 20 of the arrow *x*, Fig. 1. Fig. 3 is a view, partly in plan and partly in section, on the line *a a*, Fig. 2. Fig. 4 is a sectional plan view on the line *b b*, Fig. 1; and Figs. 5, 6, 7, 8, and 9 are views, on an enlarged scale, illustrating certain 25 features of the invention not sufficiently illustrated in the general views of the drawings.

The fixed upright frame of the machine is represented at 1, this frame having at the 30 rear bearings for the driving-shaft 2, which has fast and loose pulleys 3 and 4 for receiving the driving-belt and is also provided with a cone-pulley 5 and a spur-pinion 6, as shown in Fig. 2. The cone-pulley 5 drives by means 35 of a belt 7 a cone-pulley 9 on the shaft 10, mounted in suitable bearings at the top of the fixed frame, and said shaft has at its front end a bevel-pinion 11, which meshes with a bevel-wheel 12 at the upper end of the central 40 drill-spindle 13 of the series of spindles employed in the machine, this series in the present instance comprising three spindles—namely, the central spindle 13 and spindles 14 and 15, one on each side of the same. The 45 hub of the bevel-wheel 12 is free to turn in, but is vertically confined to, a bearing 16 at the upper end of the fixed frame 1 of the machine, and the upper end of the central drill-spindle 13 is square, splined, or otherwise 50 constructed so that it can slide vertically through the hub of said bevel-wheel, but is compelled to turn therewith. Each of the spin- dles is confined vertically to, but free to turn in, suitable bearings upon a transverse frame 17, which is connected by vertical rods 19 to a 55 yoke 20, to which is connected the forward end of a rope, cord, or chain 21, which passes over suitable pulleys 22 above the machine and carries at its opposite end a weight 23, as shown in Fig. 2, whereby the weight of the frame 17 60 and of the drill-spindles is counterbalanced and the raising and lowering of said spindles is thereby easily effected. In the present instance the central spindle 13 of the series is adapted to a fixed bearing on the frame 17; but 65 the side spindles 14 and 15 are adapted to bearings in laterally-adjustable boxes 24, which at their rear ends are provided with nuts engaged by right and left hand threads upon a screw-rod 25, which is laterally confined to a lug 70 or projection 26 at the rear of the frame 17. Hence by turning said screw-rod 25 in one direction or the other the boxes 24 can be moved from and toward each other to vary the distance apart of the drills of the series 75 75 as may be desired. The side spindles 14 and 15 have spur-pinions 27, which are driven from a spur-pinion 29 on the central spindle 13 through the medium of intervening spur-wheels 30, the spindles of which are adapted 80 to segmental slots 31 in the frame 17, as shown in Fig. 4, so that said spur-wheels 30 can be moved in or out to accord with the distance between the spur-wheels 27 and 29, nuts 32 on the lower ends of the spindles serving to 85 secure them in position after adjustment. The drill-spindles are free to move vertically 90 in bearings 33, carried by a transverse bar 34 on the fixed frame, the side bearings being adjustable laterally by means of a right and 95 left hand threaded screw-rod 35 in the same manner as the upper bearings of said spindles. A stripper-plate 36 operates in conjunction with each of the drills, these stripper-plates being secured to and depending from the 95 lower bearings 33 for the drill-spindles, as shown in Figs. 1 and 2. Vertical movement is imparted to the drill-spindles in the following manner: Between collars 37 on the central drill-spindle 13 is vertically confined a 100 cross-head 39, which is also by preference secured to the side rods 19 of the drill-carrying frame 17, so that vertical movement imparted to said cross-head will be partaken of by

all three of the drill-spindles. A pin on the back of the cross-head is connected by a link 40 to a crank-pin on a disk 41, said crank-pin being adjustable from and toward the 5 axis of the disk, so as to vary its throw in accordance with the desired extent of vertical movement to be imparted to the drills. The disk 41 is secured to a shaft 42, which is free to turn in suitable bearings on the fixed 10 frame and has secured to it a ratchet-wheel 43 and a duplex spur-wheel composed of two toothed segments 44 and 45, mounted side by side, as shown in Fig. 2, and adjustable circumferentially, the toothed portion of each 15 segment being slightly in excess of one-half of the circumference of the wheel, so that by properly adjusting these segments in respect to each other a toothed segment of any desired extent between one-half of the circumference and the entire circumference of the 20 wheel can be formed. One of the segments may be keyed or otherwise secured to the shaft 42 and the other adjusted by turning it to the proper extent in respect to the fixed 25 segment and then secured thereto by a bolt 42^a, carried by the web of one segment and entering one of a series of openings 42^b in the web of the other segment, as shown in Fig. 9. The toothed portions of both segments are 30 adapted to mesh with a wide spur-pinion 46, which is free to turn on a short shaft or stud 47 at the back of the machine, this shaft or stud also having a spur-wheel 49, which meshes with the spur-pinion 6 of the driving-shaft 2. 35 When the spur-pinion 46 is in mesh with the toothed portions of the segments 44 45 or either of them, therefore power will be transmitted to the shaft 42 through the medium of the spur-gearing shown and described; but 40 when a blank portion of the duplex segment-wheel is presented to the spur-pinion 46 other means must be resorted to for rotating said shaft 42. For this purpose, therefore, the ratchet-wheel 43 is engaged by spring-pawls 45 50, hung to the face of a worm-wheel 51, which is mounted so as to turn loosely on the shaft 42 and meshes with a worm 52 at the lower end of a short vertical shaft 53, which has at its upper end a bevel-wheel 54, meshing with 55 a bevel-pinion 55 on a transverse shaft 56, the latter having at its rear end a pulley driven by a belt 57 from a pulley on the top shaft 10 of the machine. A slow and powerful movement can therefore be imparted to the disk 55 60 41, this movement being that employed when the drills are descending and acting upon the work, quicker movement of the drill-spindles being effected at other times by means of the direct spur-gearing connection between 65 the driving-shaft and the shaft 42, the teeth of the ratchet-wheel 43 in this case slipping under the pawls 50. The worm-shaft 53 has its upper bearing in a fixed portion of the frame of the machine; but the lower bearing 65 of said shaft is in an eccentric sleeve 59, mounted in a bearing on the fixed part of the machine, as shown in Fig. 6, the upper col-

lar 60 of said eccentric sleeve having a handle 61, whereby it may be turned in its bearing, and said handle being provided with a 70 spring-actuated locking-bolt 62, which by engagement with suitable notches in the top of the bearing will serve to retain the eccentric sleeve in different positions of adjustment. By turning the sleeve, therefore, the worm 52 75 can be moved out of engagement with the worm-wheel 51 when it is desired to effect such release, the spring of the shaft permitting such movement. As the duplex segment-wheel of the shaft 42 is when said shaft is being 80 operated by the worm-gearing described moving at a slower rate of surface speed than the pinion 46, I find it advisable to use for the first tooth of the segment 44 a yielding or elastic tooth which as it is gradually brought 85 into position to mesh with the teeth of the pinion 46 will be free to spring or yield when the teeth of said pinion 46 first come into contact with the same and act only upon the crown of it, the teeth finally meshing with a tooth of 90 the pinion when the segment has been moved forwardly to such an extent as to permit of the proper hold of the tooth of the pinion upon it. This spring-tooth is shown in Fig. 95 5 of the drawings and consists of a plate 63, secured to the blank portion of the periphery of the segment and bent backward upon itself, as shown at 64, to form a proper tooth outline, a recess 65 in the periphery of the disk permitting the springing inward of the 100 tooth to the limited extent required before a tooth of the pinion 46 can properly mesh with the same.

The work-carrying table or bed 66 of the machine is guided in the fixed structure 67, 105 which is located in advance of the lower portion of the upright frame 1 of the machine, longitudinal reciprocating movement of said table or bed being effected by engagement of a nut on the under side of the same with a longitudinal screw-shaft 69, which turns in bearings in the structure 67, as is common in mechanism for reciprocating the tool-carriages of lathes and similar metal-working tools. The nut which engages with the feed-screw 59, however, is of the peculiar duplex 110 construction shown in Fig. 7, and comprises two brackets 70 and 71, mounted on the under side of the table 66 and each terminating at its lower end in a nut engaging the screw-shaft 69. The bracket 70 is fixedly secured to the table; but the bracket 71 is adjustable from and toward the bracket 70 by means of a transverse bolt 72 and nut 73. Hence the two parts of the nut can be moved from and 115 toward each other to compensate for any wear of the threads of either the screw 69 or of the nuts of the brackets, so that close fit of the screw to the opposite nuts is thereby insured and any backlash or play of one in respect 120 to the other is effectually prevented.

On the main table or bed 66 is mounted a pair of transverse guides 75, each provided with a central screw-shaft 76, and each of

these screw-shafts engages with a nut 77, as shown by dotted lines in Fig. 3, said nuts being formed on or connected to the under sides of the plates 79, which are free to slide in the guides 75 and carry opposite longitudinal rails 90 and 91, preferably of the angular cross-section shown in Fig. 2, the rail 91 having confining-bolts 92, whereby the plate or other object to be drilled can be confined between the two rails.

Movement of the work-table or bed in its guides and of the work-carrier in the direction transverse to the movement of said work-table or bed is effected by the return or rising movement of the drill-spindle carrier, the mechanism for causing this result being as follows: Vertically confined between collars 93 on the central drill-spindle 13 is a sleeve 94 on the fixed frame and has at the back a rack 95, passing through a slot in said bearing and meshing with a spur-pinion 96 on a short transverse shaft 97, which is provided at its outer end with a chain-wheel 99, said wheel receiving a chain belt 100, which drives a similar chain-wheel 101, secured to a shaft 102, mounted in suitable bearings in the upright frame 1 of the machine, said shaft having secured to it a hub with arms 103, which are adapted by contact with pins 104 on a chain-wheel 105, loose on the shaft 102, to turn said chain-wheel forwardly or in the direction of the arrow shown in Fig. 2. One of the arms 103 also plays between one of the pins 104 and a set-screw 106, carried by a stud 107 on the face of the chain-wheel 105. Hence said arm is also capable of imparting backward movement to said chain-wheel, the distance between the end of the set-screw 106 and the stud 104 representing lost motion of the arm in changing from forward to backward or backward to forward movement of said chain-wheel 105, this lost motion representing the movement of the drill-spindle carrier necessary to effect the withdrawal of the drills from the work, since it is manifest that there can be no feed of the latter in any direction until the drills have thus been withdrawn from it. The chain-wheel 105 receives a chain belt 109, which drives a chain-wheel 110 on a shaft 111, mounted in bearings in a standard 112 and in the upright frame of the machine, said chain-wheel 110 having sprung-pawls 113, which engage with a toothed disk 114 on the shaft 111, the chain-wheel 110 being free to turn in either direction upon said shaft. The various chain-wheels are so proportioned that each lift of the drill-spindle carrier will impart to the chain-wheel 110 movement to the extent of at least one-half a revolution in each direction, so that by reason of the pawls 113 and toothed disk 114 intermittent forward movements of a half-turn will be imparted to the shaft 111. The said shaft 111 has at its outer end a spur-wheel 115, which meshes with a spur-wheel 116, the latter meshing with a spur-pinion 117 on a

shaft 119, which is mounted in bearings in a standard or bracket 120, the shaft or spindle of the spur-wheel 116 being adapted to a longitudinal slot 121 in a lever 122, which is hung to the shaft 119 and has a slotted segment 123 for the reception of a stud on the fixed frame, to which stud the segment can be secured by means of a nut 124 thereon. This construction provides for the use of spur-wheels 116 and 117 of any desired size, which thus constitute change-wheels whereby the half-revolutions imparted to the spur-wheel 115 may be caused to impart any desired fraction of a revolution to the shaft 119, depending upon the amount of feed of the table 66 required between successive actions of the drills. The shaft 119 has another spur-wheel 125, which meshes with a spur-wheel 126, carried by one arm of a lever 127, which is hung to a bearing on the structure 67, the other arm of said lever having a spur-wheel 129, which is constantly in mesh with the spur-wheel 126. The outer end of the lever 127 is connected by means of a link 130 to a radially-adjustable crank-pin 131 on a disk 132, carried by the outer end of a shaft 133, which is adapted to suitable bearings on the front of the structure 67 and has another spur-wheel 134, which when the table 66 is at one limit of its movement meshes with a spur-pinion 135 on a shaft 136, mounted in suitable bearings in brackets secured to the guides 75 of said table 66, said shaft 136 having another pinion 137, with which the spur-wheel 134 meshes when the table 66 is at the opposite limit of its movement. The shaft 136 also has bevel-pinions 140, which mesh with corresponding bevel-pinions 141 at the front ends 105 of the feed-screw shafts 76 of the guides 75, and the rear ends of said screw-shafts have bevel-pinions 142, which mesh with similar bevel-pinions 143 on a shaft 144, adapted to bearings in brackets at the rear ends of the guides 75, said shaft 144 having spur-pinions 145 and 146, which alternately mesh with a toothed segment 147 on a shaft 149, adapted to a bearing in the upright frame 1 of the machine, the pinion 145 meshing with said toothed segment when the table 66 is at one limit of its movement and the pinion 146 meshing with the toothed segment 147 when the table 66 is at the opposite end of its movement. The shaft 149 receives movement from the shaft 111 through the medium of intermeshing spur-pinions 150 and 151, as shown in Fig. 3. When the work-carrier is at either limit of its longitudinal travel, therefore, the feed-screws 76 of the guides 75 will have movement imparted to them sufficient to give the desired transverse movement to the work-carrier, and at the same time the shaft 136 will be operated, so as to impart movement of partial rotation to the shaft 133, this movement being sufficient to carry the crank-pin 131 of the disk 132 throughout a half-turn—that is to say, from bottom to top or top to bottom—of the disk, thereby effecting a rocking of the

- lever 127 and causing the spur-pinions 126 and 129 to engage alternately with the spur-wheel 152 at the outer end of the feed-screw 69, which operates the main table 66. When 5 the lever 127 is in the position shown in Fig. 2, the spur-pinion 126 is the only one intermediate between the spur-wheel 125 and the spur-wheel 152; but when the lever has been shifted so as to carry the pinion 126 out of 10 mesh with the spur-wheel 152 and the pinion 129 into mesh therewith both of the pinions 126 and 129 will be interposed between the spur-wheel 125 and the spur-wheel 152. Consequently the feed-shaft 69 will be rotated in 15 a direction the reverse of that which it receives when the parts are in the position shown in Fig. 2. Proper reversal in the direction of rotation of the feed-screw is thus provided for at each end of the travel of the table 66, 20 and at the same time the work-carrier is moved transversely to the feed-table, so that after forming one row of openings in a plate or other object during one movement of the table 66 another row of openings in a different 25 plane is formed therein on the reverse movement, and so on until any desired number of rows has been produced. A complete spur wheel or pinion may be used instead of the segment 147, if desired.
- 30 In the drawings I have shown a series of three drills arranged side by side in the same plane; but the number and grouping of the drills may be varied in accordance with the character of the work to be performed. The 35 transverse guides 75 are also shown as inclined at an angle other than a right angle to the table or bed 66; but it will be evident that the angle of these guides may be varied as desired and a single transverse guide may be 40 used, or, on the other hand, more than two of these guides may be employed.
- In order to prevent any possibility of backward movement of the shaft 111, due to the 45 frictional hold of the chain-wheel 110 thereon while said chain-wheel is being turned backwardly, I provide the said shaft with a notched collar 153, as shown in Fig. 1, this notched collar engaging with a sliding spring-bolt 154, mounted in the bearing 112, when 50 said shaft 111 comes to rest after having completed a forward half-turn. Hence the shaft is effectually locked against any backward movement which would interfere with the proper operation of the feed-screws of the 55 work table or carrier.
- It will be observed that my improved machine is wholly automatic in its action, that the feeding of the work is positive in each direction, and that all desired facilities are 60 provided for adjustment of the work in respect to the drills or for adjustment of the latter in respect to the work. Hence the machine is capable of performing a wide range of operations.
- 65 Having thus described my invention, I claim and desire to secure by Letters Patent—

1. The combination in a vertical drilling-machine, of a drill-spindle, means for vertically reciprocating the same, a work-table, a 70 work-holder guided transversely on said work-table, feed-screws for the work-table and work-holder, and gearing whereby the vertical movement of the drill-spindle is caused to impart movement to said feed-screws, substantially as specified.

2. The combination, in a vertical drilling-machine, of a drill-spindle, means for rotating and vertically reciprocating the same, a work-table and longitudinal feeding devices 80 therefor having as elements a spur-wheel on the feed-screw, a driving spur-wheel, and a lever carrying two spur-pinions meshing together, one of said pinions being also in mesh with the driving spur-wheel, whereby the rocking of the lever will permit either of its spur-pinions to mesh with the spur-wheel of the feed-screw in order to reverse the direction of rotation of the same, substantially as specified.

3. The combination, in a vertical drilling-machine, of a drill-spindle, means for rotating and for vertically reciprocating the same, a work-table, and feed-gearing interposed between the vertically-reciprocated spindle and the work-table, one of the elements of said gearing being a lost-motion clutch whereby feed movement of the table will be arrested until the drill is withdrawn from the work, substantially as specified.

4. The combination, in a vertical drilling-machine, of a drill-spindle, means for rotating and for vertically reciprocating the same, a work-table, and feed-gearing interposed between the drill-spindle and the work-table 105 and having as elements a pawl-and-ratchet clutch whereby movement is imparted to the feed-screw only when the drill-spindle is reciprocating in one direction, substantially as specified.

5. The combination, in a vertical drilling-machine, of a drill-spindle, means for rotating and vertically reciprocating the same, a work-table, a feed-screw therefor, and gearing interposed between the drill-spindle and said feed-screw, and serving to transmit movement from one to the other, elements of said gearing being change-wheels whereby the extent of movement of the feed-screw on each reciprocation of the drill-spindle can be varied, substantially as specified.

6. The combination, in a vertical drilling-machine, of a drill-spindle, means for rotating the same, and reciprocating devices for said drill-spindle comprising a shaft having 115 a spur-segment thereon, a pinion for driving the same, a loosely-running and continuously-driven worm-wheel on said shaft, and a one-way-clutch connection between said worm-wheel and the shaft, substantially as 120 specified.

7. The combination, in a vertical drilling-machine, of the drill-spindle, means for rotating the same, and reciprocating devices for

the spindle comprising a shaft and two independent driving devices therefor, one having a one-way clutch whereby it is connected to the shaft and the other having an adjustable spur-segment comprising two members each with partially-toothed periphery, said members being adjustable circumferentially on the shaft so as to increase or diminish the extent of toothed segment presented, substantially as specified.

8. The combination in a drilling-machine, of a drill-spindle, means for rotating the same, and reciprocating devices for said drill-spindle comprising a shaft having a toothed segment whose leading tooth is yielding and elastic, a pinion for driving said segment, means whereby rotation of the shaft is caused to impart reciprocating movement to the drill-spindle, and gearing for rotating the shaft when its segment is out of mesh with the driving-pinion, substantially as specified.

9. The combination in a drilling-machine, of a drill-spindle, means for rotating the same, and reciprocating devices for said drill-spindle comprising a shaft having a toothed segment whose leading tooth is composed of a bent plate of spring metal mounted above a recessed portion of the periphery of the segment, a pinion for driving said segment, means whereby the rotation of the shaft is caused to impart reciprocating movement to the drill-spindle, and gearing for rotating the shaft when its segment is out of mesh with the driving-pinion, substantially as specified.

35 10. The combination, in a vertical drilling-machine, of the work-table, means for reciprocating the same, a work-holder, guides

therefor, disposed transversely of the feed-table, transverse feeding devices for the work-holder, and gearing whereby said feeding devices are rendered operative when the work-table reaches the limit of its movement in either direction, substantially as specified.

11. The combination, in a vertical drilling-machine, of the feed-table, means for reciprocating the same, a work-holder, guides for said work-holder disposed transversely of the feed-table, work-holder-feeding devices, gearing for operating the same at either limit of movement of the feed-table, reversing-gearing for the feed-table, and gearing whereby said reversing devices are operated by the work-holder-feeding mechanism at either end of the travel of the feed-table, substantially as specified.

12. The combination, in a vertical drilling-machine, of the drill-spindle, means for rotating and for vertically reciprocating the same, a work-table, feeding devices therefor, and feed-operating gearing interposed between the drill-spindle and said work-table-feeding devices and having as elements a one-way clutch whereby forward movement is imparted to the feeding devices, and a spring-lock whereby backward movement of said feeding devices is prevented, substantially as specified.

In testimony whereof I have signed my name to this specification in the presence of two subscribing witnesses.

DANIEL RAMSAY.
